UNITED STATES PATENT OFFICE.

HENRY L. DAY, OF MINNEAPOLIS, MINNESOTA.

RELIEF-VALVE FOR SUCTION OR BLAST PIPES.

SPECIFICATION forming part of Letters Patent No. 650,670, dated May 29, 1900.

Application filed August 7, 1899. Serial No. 726,380. (No model.)

To all whom it may concern:

Be it known that I, HENRY L. DAY, of Minneapolis, county of Hennepin, State of Minnesota, have invented certain new and useful 5 Improvements in Relief-Valves for Suction or Blast Pipes, of which the following is a specification.

My invention relates to relief-valves for use in connection with the suction or blast pipes 10 for conveying materials—such as sawdust, shavings, or dust from machines in wood-working shops, elevators, or other places—to storage-rooms or to boiler-furnaces or to other suitable receptacles for such materials, and is 15 designed as an improvement over a similar device shown and described in Letters Patent of the United States No. 503,126, granted to me August 15, 1893.

The object of the invention is to provide a 20 mechanism that is more simple in construction than the device described in the above-named patent and will therefore be easier and cheaper to manufacture, though accomplishing substantially the same result.

25 The invention consists generally in a valve chamber or box having a valve, a main inlet-opening, and a divided outlet-opening, in combination with an elbow or curved section of pipe whose wall acts as a deflector to direct a 30 portion of the air and the heavier or coarser material through one section of the valve-chamber and permit the surplus air and lighter material to pass through another section, and a fan or fans in connection with said pipe, all 35 as hereinafter described, and particularly pointed out in the claims.

In the accompanying drawings, forming 40 part of this specification, Figure 1 is a longitudinal section of the valve-box embodying my invention and the pipe-section and fan-casing with which said box is connected on the line $y-y$ of Fig. 2. Fig. 2 is a longitudinal section on the line xx of Fig. 1.

In the drawings, 2 represents a fan, and 45 its casing, of any preferred size and construction, and said fan may be located at any desired distance from the relief-valve and in any preferred position to draw material from wood-working machinery in the usual manner.

50 5 is the valve-chamber, arranged at any preferred point in the blast-pipe and having an in-

let-opening 6 and a discharge-opening 7, communicating with pipes 8 and 9, one of which may lead to a furnace-boiler and the other to 55 a storage-bin or warehouse, where the shavings and heavier material may be accumulated until needed. At a point in the blast-pipe near the inlet-opening to the valve-chamber I provide a curved pipe-section 4, whose wall 60 acts as a deflector to divert the heavier material that is thrown against it and direct the same, with a portion of the air-blast, into one section of the valve-chamber. Within said chamber I prefer to provide a horizontal plate 65 10, centrally arranged and dividing said chamber into an upper and lower compartment or passage, and on said plate I provide a valve 11, vertically pivoted on the rod 12 and operated by a crank 13. This valve, as shown 70 in Fig. 2, is pivoted, preferably, near the middle of the plate 10 and serves to divert the shavings and heavier material into either of the pipes 8 or 9, the material being directed into the space above said plate by contact with 75 the curved wall of said pipe-section, as heretofore described. Should the valve 11 be parallel with the longitudinal axis of said valve-chamber, the heavier material will be distributed between the two pipes 8 and 9. Should 80 the valve be in the position indicated in full lines in Fig. 2, all of the heavier material will be directed into the pipe 9 or into the pipe 8 should the valve be in position indicated by dotted lines in said figure. While the heavier 85 particles are being deflected from the curved surface of the section 4, a portion of the air-blast and the lighter particles and dust held in suspension thereby will pass beneath the plate 10 and into the pipes 8 and 9. 90

By providing a curved pipe or elbow in the blast-pipe at a point near the valve-chamber I utilize the curved wall as a deflector, and thus dispense with an independent plate for that purpose; but I do not wish to confine myself 95 to any particular form or degree of the curved section, it being necessary simply to provide such an angle in the pipe to cause the heavier particles that are thrown against the wall of the pipe to be deflected to a point where they 100 may be directed to a furnace-boiler or storage-bin, as preferred.

I have shown but one form of valve-chamber and arrangement of valve therein; but

obviously the position of the valve may be varied, according to the relative positions of the valve-chamber and the curved section of the blast-pipe, and while I have shown a single fan connected with the blast-pipe obviously two or more fans may be employed and the valve-chamber located at any preferred distance from said fan and in any preferred position with respect to said fan, and the various details of the valve-chamber, such as the means for operating the valve to its position in the chamber, may be varied by any one skilled in matters pertaining hereto, and I therefore do not wish to confine myself to the specific construction herein described.

Having thus described my invention, I claim as new and desire to secure by Letters Patent:—

1. The combination, with a valve-chamber having an inlet-opening and divided outlet-openings and a valve provided in said valve-chamber, of a curved pipe-section provided in the blast-pipe near said inlet-opening, the wall of said section acting as a deflector to direct a portion of the air-blast, and the heavier materials thrown against it, to one section of the valve-chamber while the surplus air and lighter material pass to another section of the valve-chamber, and a fan or fans connected with said blast-pipe, substantially as described.

2. The combination, with a valve-chamber, having an inlet-opening and a divided outlet-opening, means provided within said valve-

chamber for directing a portion of the air- 35 blast into either of said outlet-openings, a curved pipe-section provided in the blast-pipe near said valve-chamber, the wall of said pipe-section acting as a deflector to direct a portion of the air, and the heavier material carried thereby, which is thrown against said wall, to one section of said valve-chamber while permitting the surplus air and the lighter material to pass into another section, and a fan or fans provided in connection with 45 said blast-pipe, substantially as described.

3. The combination, with a valve-chamber having inlet and outlet openings and pipes 8 and 9 connected to said outlet-opening, of a plate 10 provided in said chamber, a valve 50 11, means for operating the same, a curved pipe-section provided in the blast-pipe near the inlet - opening of said valve - chamber whereby when the air-blast passes through the same the heavier material will be thrown 55 against the curved wall of said section and deflected into the space above said plate 10 to be directed by said valve into either of said outlet-pipes 8 or 9, while the surplus air and lighter material carried thereby pass through 60 said chamber beneath said plate, substantially as described.

In witness whereof I have hereunto set my hand this 14th day of April, 1899.

HENRY L. DAY.

In presence of—
RICHARD PAUL,
M. C. NOONAN.
